UNITED STATES PATENT OFFICE.

WILHELM KRAUS, OF BERLIN-CHARLOTTENBURG, GERMANY.

TOBACCO.

1,201,831.

Specification of Letters Patent. Patented Oct. 17, 1916.

No Drawing.

Application filed November 30, 1915. Serial No. 64,316.

To all whom it may concern:

Be it known that I, WILHELM KRAUS, a subject of the Emperor of Austria-Hungary, and residing at Bleibtreustrasse 13/14, Berlin-Charlottenburg, Germany, have invented certain new and useful Improvements in or Relating to Tobacco, of which the following is a specification.

This invention relates to a new or improved method of removing nicotin from tobacco.

The processes for de-nicotinizing tobacco known up to the present are attended with the drawback that the extraction of the nicotine results in the aroma and flavor of the tobacco or tobacco products treated being impaired. Apart from this, such processes as have hitherto been made public involve manipulation or manual labor of a rather troublesome nature which renders them uneconomical in practice.

The new or improved de-nicotinizing process is distinguished from all those heretofore known by its intrinsic simplicity and the valuable technical effect attained. It is more particularly adapted for dealing with raw material for pipe and cigar tobaccos and snuff tobaccos.

The process is in essentials carried out substantially in the following manner:—The raw materials to be treated are placed in a vacuum chamber adapted to be heated, as by steam or electric current. A vacuum chamber such as is used for desiccating dried vegetables is best adapted for this purpose. After charging the chamber with the tobacco leaves a vacuum is maintained for about half an hour, the temperature being kept constant at from about 25 to 30° C. This is done with the object of preparing the tobacco for the following operations.

When the air has been extracted from the chamber to a sufficient extent a previously prepared supply of saturated lime water to which 1% of calcium nitrate has been added is allowed to flow in from a containing vessel by opening a valve provided on the vacuum chamber. This liquid is allowed to remain in contact with the tobacco for about thirty minutes, the original vacuum and the temperature specified being maintained. The lime water destroys on one hand the amid substances contained in the tobacco and on the other hand splits off the malate or citrate of nicotin without destroying the aromatic substances, as lime water is

a comparatively weak alkali. The addition of calcium prevents on one hand or minimizes the removal by lixiviation of the other organic acids and resins which have a beneficial effect on the aroma and flavor of the tobacco leaves, and on the other hand insures complete combustion of the tobacco products when smoked later on. During this operation free nicotin and in addition ammonia are evolved, both being partially withdrawn by the continuous removal of air.

After a predetermined time the vacuum is destroyed and the lime water run off. The air is then again withdrawn and a 0.5% solution of formaldehyde admitted to the chamber and allowed to act on the tobacco for about five minutes in order to take up, by combinining therewith, the ammonia absorbed by the tobacco and which cannot be wholly removed even in the subsequent process of drying the tobacco leaves. The tobacco is then withdrawn from the vacuum chamber and placed in the drying room where it is thoroughly dried at 40° C. after being previously stripped in the case of cigar tobaccos. In this drying process the nicotin previously liberated escapes along with the water vapor.

By means of this process it is possible to obtain without difficulty a reduction of from 40 to 50% of the amount of nicotin while fully preserving the specific smoking aroma and at the same time improving the burning qualities of the tobacco. It is obvious that by repeating the process the loss of nicotin can be still further increased.

What I claim is:—

1. A process for de-nicotinizing tobacco leaves according to which the tobacco is treated in a vacuum with a solution of calcium nitrate in saturated lime water and then dried.

2. A process for de-nicotinizing tobacco according to which the tobacco is treated in a vacuum with a solution of calcium nitrate in saturated lime water, is then treated with a solution of formaldehyde and is finally dried.

3. A process for de-nicotinizing tobacco according to which the tobacco is treated in a vacuum with a solution of approximately 1% strength of calcium nitrate in saturated lime water, and then dried.

4. A process for de-nicotinizing tobacco according to which the tobacco is treated in a vacuum with a solution of approximately

1% strength of calcium nitrate in saturated lime water then treated with a 0.5% solution of formaldehyde, and is finally dried.

5. In de-nicotinizing tobacco placing the tobacco in a heated vacuum chamber and subjecting it therein to a temperature of about 25° to 30° C. for about half an hour, then causing saturated lime water containing about 1% of calcium nitrate to flow in the vacuum chamber, from which air has been previously exhausted, and allowing the lime water to remain in contact with the tobacco for about half an hour while maintaining the vacuum and the temperature, then allowing air to enter the vacuum chamber and withdrawing the tobacco and finally drying the tobacco at a temperature of about 40° C.
6. In de-nicotinizing tobacco placing the tobacco in a heated vacuum chamber and subjecting it therein to a temperature of about 25° to 30° C. for about half an hour, then causing saturated lime water contain-

ing about 1% of calcium nitrate to flow in the vacuum chamber, from which air has 25 been previously exhausted, and allowing the lime water to remain in contact with the tobacco for about half an hour while maintaining the vacuum and the temperature, then destroying the vacuum in the chamber 30 and running off the lime water afterward admitting a 0.5% solution of formaldehyde to the vacuum chamber after again withdrawing air therefrom and allowing the formaldehyde to act on the tobacco for about 35 five minutes, then allowing air to enter the vacuum chamber and withdrawing the tobacco and finally drying the tobacco at a temperature of about 40° C.

In testimony whereof I affix my signature 40 in presence of two witnesses.

WILHELM KRAUS.

Witnesses:

HENRY HASPER,
ARTHUR SCHROEDER.
